DESIGN.

H. C. BASCOM & F. RITCHIE.
HEATING STOVE.

No. 20,424.

Patented Dec. 23, 1890.

UNITED STATES PATENT OFFICE.

H. CLAY BASCOM, OF LANSINGBURG, AND FRANCIS RITCHIE, OF TROY,
NEW YORK.

DESIGN FOR A HEATING-STOVE.

SPECIFICATION forming part of Design No. 20,424, dated December 23, 1890.

Application filed September 8, 1890. Serial No. 364,354. Term of patent 3½ years.

To all whom it may concern:

Be it known that we, HENRY CLAY BASCOM and FRANCIS RITCHIE, citizens of the United States, residing, the said BASCOM at the village of Lansingburg, county of Rensselaer, and State of New York, and the said RITCHIE at the city of Troy, in said county and State, have invented and produced a new and original Design for Heating-Stoves, of which the following is a specification, reference being had to the accompanying drawing, forming a part thereof, and consisting of a single figure affording a view in perspective of our newly-designed stove.

15 The leading features of our new design consists in the configuration and ornamentation of the various parts.

The general form of the stove-base A is approximately that of a square with rounded corners. The ash-pit A' is in the form of a frustum of a pyramid, with its base smaller than the stove-base, the sides of the base and ash-pit being parallel with each other. Mounted upon the ash-pit are the circular fire-pot A² and the combustion-chamber A³, similar to each other in form, the fire-pot expanding upward and the combustion-chamber expanding downward, the expanding members being separated from each other by the circular exterior flange A⁴. The combustion-chamber is surmounted by an upwardly-expanding circular heating-chamber A⁵, having a circular top flange A⁶. The legs A⁷ are each provided with a shell ornament A⁸, centrally located on the upper face, and with a foliated face ornament A⁹ on each of the upper side extremities of the leg. The sides of the base are provided with a lower border-rib B and a series of vertical ribs B', the individual ribs extending from the border-rib to the top of the base. The sides of the ash-pit are ornamented with horizontal parallel rows of projections B², each projection having a vertical face semicircular in form, the rows being arranged in terraces one above the other. The lower portion of the front side has elongated draft-openings B³ and the upper portion a horizontal plain panel B⁴. The fire-pot has at its upper end and at its lower end a plain

horizontal band and intermediately of such bands a horizontal row of vertical ribs or corrugations B⁵. The circular flange A⁴ has a lower border-rib B⁶ and a series of vertical ribs B⁷, the individual ribs extending from the border-rib to the top of the flange. The combustion-chamber has a lower horizontal border row of vertical ribs or corrugations C and an upper horizontal border row of triangular-shaped ornaments C', the border rows of ornaments being separated by a plain horizontal band C². The expanding heating-chamber has its middle part C³ cylindrical in form, and the top flange has a lower border-rib C⁴ and a series of vertical ribs C⁵, the individual ribs extending from the border-rib to the top of the flange.

What we claim as new is—

1. The design for a heating-stove herein shown and described, consisting of a four-sided base with rounded corners surmounted by an ash-pit in the form of a frustum of a pyramid, with its sides parallel with and shorter than the sides of the base, a circular upwardly-expanding fire-pot rising from the ash-pit and having an upper and lower plain horizontal border-band and a horizontal row of vertical flutes between such bands, a circular downwardly-expanding combustion-chamber above and separated from the fire-pot by a circular flange and having a lower horizontal border row of corrugations, an upper horizontal border row of ornaments, and a plain horizontal band between such rows, and a circular upwardly-expanding heating-chamber surmounting the combustion-chamber. 85

2. In a design for a heating-stove, the design for an ash-pit herein shown and described, consisting of the frusto-pyramidal form with parallel terrace rows of ornamental projections having vertical semicircular faces on its sides and on one side a horizontal row of draft-openings beneath a plain horizontal panel. 90

3. In a design for a heating-stove, the design for a combustion-chamber herein shown and described, consisting of the circular downwardly-expanding form with a lower horizontal border row of vertical ribs, an upper

horizontal border row of triangular-shaped ornaments, and a plain horizontal band intermediately of the ornamental border rows.

4. In a design for a heating-stove, the design for a leg herein shown and described, consisting of a central shell ornament on the upper leg-face and a foliated face ornament on the upper side extremities of the leg.

In testimony whereof we have hereunto set our hands this 6th day of September, 1890.

H. CLAY BASCOM,
FRANCIS RITCHIE.
